UNITED STATES PATENT OFFICE.

ALVIN E. HESS, OF BLOOMSBURG, PENNSYLVANIA.

RAILWAY-TIE.

1,277,930.

Specification of Letters Patent. Patented Sept. 3, 1918.

Application filed January 25, 1918. Serial No. 213,759.

To all whom it may concern:

Be it known that I, ALVIN E. HESS, a citizen of the United States, residing at Bloomsburg, in the county of Columbia and State of Pennsylvania, have invented new and useful Improvements in Railway-Ties, of which the following is a specification.

This invention relates to railway ties, and more especially to those which are composite because they are made up of a plurality of materials; and the objects of the same are to produce a tie of metal and wood and each in two parts and detachably connected and adjustable to a certain extent so that the wooden parts can be removed and replaced when worn, to prevent movement of the tie either longitudinally or transversely, to cause it to cling to the road bed, to permit the metal parts to be set up yet a little closer together and more tightly on the wooden parts without removing the tie from the roadbed, to produce a tie whose parts can be easily stored or can be assembled in the store house or on the job where the trackway is being laid, and finally to simplify the whole and reduce its cost of expense.

These various objects are carried out by constructing the composite tie in the manner hereinafter more fully described and claimed, and as shown in the drawings wherein:—

Figure 1 is a perspective view of a section of railway track whereof the rails are laid on ties embodying my invention, the road bed being removed from part of one tie to show its end from the exterior, and the roadbed and the end of the next tie being broken away to give a sectional view of the nearest block and the bolt through it.

Fig. 2 is an end elevation of the parts of this tie slightly separated.

Fig. 3 is a cross section through the same parts when they are connected.

Fig. 4 is a bottom view of the tie showing the swinging links which connect its metallic parts.

This improved tie is made up of two complementary metal members, two wooden blocks, two bolts connecting the members with the blocks, and one or more links which latter are preferably although not necessarily employed. While we prefer that the blocks shall be of wood, and wood which is treated so as to prevent the deleterious effects of climate, moisture, grease from the

passing trains, and the like; I do not wish to be limited to blocks of wood as they might be of other material. The metal members may be rolled or cast. While they are shown assembled edge to edge, they are exact duplicates of each other, and therefore one set of dies would answer for rolling and one mold for casting. The proportions and details are not essential to the present invention.

Each metal member is substantially L-shaped in cross section, its upright web 1 being substantially four inches high (more or less) and as long as may be necessary and preferably beveled off at the ends as at 2, and at properly spaced points this web is provided with openings for the bolts yet to be described. The horizontal web is a narrow strip 3 standing substantially at right angles to the upright web. Between these webs is what I call a lip which may easily be formed as shown in the sectional views if the metal member is rolled, and this lip 4 as a whole stands nearly horizontal but projects outward and slightly downward from the line along which the upright and horizontal webs meet. In its formation, the lower edge of the upright web is carried outward and downward to form the upper leaf of the lip, and turned upward a little at its extreme edge as shown at 5, and then it is carried directly backward and beneath the upper leaf to form the lower leaf of the lip, and merges by an obtuse angle into the lower web 3 as shown. The extremities of the upper leaf are downturned as at 6 and form flanges which embed the ballast B of the railway so as to prevent the tie from creeping or other movement longitudinally, and the ballast overlies the lip and is caught behind its upturned outer edge so as to prevent the tie from rising undesirably. Thus the metal member is made if it is rolled. If it be cast, the upright and horizontal webs would doubtless be integral with the lip, the latter slightly oblique to both as shown, and its outer edge rolled upward, but it would not be in two leaves. The inclination of the lip causes the bottom of the tie to be channeled as it were so that it rests firmly on the roadbed or ballast B, and the whole tie is embedded within said ballast as seen at the rear of Fig. 1. There are two of these metal members, with their horizontal flanges placed edge to edge but not quite in contact.

Each wood member is a block 10, preferably rectangular and substantially of the relative size shown in the drawings, and as above suggested these blocks should be treated to prevent them from decay. Each block squarely underlies one of the rails R, and its height is such that it rises above the upper edges of the upright webs for an inch or two so that the rails never touch the metal 10 of the tie. The blocks should be of sufficient length to permit the spikes S to be driven into them without splitting the blocks. The latter are held between the upright webs of the two metal members by transverse bolts 15 11 passing through the holes in said webs and through appropriate holes in the blocks, and by preference we make the holes 12 in the upright webs rather larger than the shanks of the bolts vertically, and in the 20 form of slots as seen, for a purpose which will appear. When this tie is to be used where switches or cross-overs occur, the metal members will be a little longer than normally employed and pierced with more 25 openings than shown, and longer blocks will be used so that the four rails may be spiked thereto, two by two, as understood. Further along a switch where the rails of the two tracks have diverged to a considerable 30 extent, the metal members may be quite long and four separate blocks employed; but always we would have the holes through the upright webs slotted vertically so that, in case the blocks become loose or worn, they 35 may move vertically but they may not move horizontally which would throw the track out of gage. By this it will be understood that in time the blocks may become compressed to a certain degree, especially if they 40 are dried out by a long season of hot weather or if the traffic has been extremely heavy and the blocks are old. Their lower sides rest squarely on the horizontal webs 3, and their side faces are supposed to contact with 45 the inner faces of the upright webs 1. If their upper faces descend under the shrinkage of the blocks as suggested, it is desirable that the bolts shall descend with them in the openings in the upright webs, rather 50 than be sheared off as might occur if the bolts fitted the openings rather closely. Obviously the track-walker or other attendant will from time to time set up the nuts on the bolts to make them tight, or at stated 55 periods a track gang can travel the length of the stretch of track and do all this work at once.

The devices above described will connect the two metal members and the interposed 60 wooden members, but by preference we also employ links as seen in Fig. 4, each of which is constructed as follows:—The link has a substantially upright flat body 20 of a length to extend across the horizontal webs 65 of the two metal members between their

lips, and possibly beveled or inclined at its extremities at 21 so as to underlie said lips partly, and at appropriate points having two tangs or pins 22 rise from the upper edge of this link and pass through holes 23 70 in the lower web, one or both of them being upset or riveted at their upper ends as seen at 24. There may be one or more of these link connections between the metal members of each tie, but by preference I dispose each 75 a little obliquely when it is put in originally, and this may be brought about by cutting the holes in the lower web in a slightly staggered relation with each other. The material of which the link is formed is not essential, 80 excepting that we would prefer metal and it should not be cast metal because that would not permit the upsetting or riveting of its tangs.

A composite or compound tie as thus constructed has many advantages. First its metal members may be easily made by rolling or casting them, and easily stored in small compass because one would nest very nicely within another. The bolts and the 90 links are of course separate from the members at this time. The wooden blocks need not be stored, nor need they be provided until the ties are to be laid. At that time they can be cut from appropriate pieces of available wood, whether treated or not, although we would prefer to have them treated with some creosote or other composition which will prolong their life and render them impervious to moisture and other deleterious 95 exterior influences. In fact the blocks need not fit between the members very accurately, and this is one of the principal points of advantage of my tie. If they are little higher or longer than shown in Fig. 1, it obviously 100 makes no difference. If they are a little wider, it would only cause the metal elements to stand a little farther apart, the nuts would not be run so far onto the bolts, and the oblique link if employed would not stand 105 quite at the angle across the tie as shown in Fig. 4. In fact, it may be well to have the blocks a little oversize rather than a little undersize, because when they become loose as suggested above they then may be 110 more readily tightened up without throwing the lower webs into contact, edge to edge, and of course the longer and stronger the blocks the less apt they are to be split by the spikes S and by heavy traffic and bad 115 weather. In laying the tie the parts may be assembled in the shop or may be brought to the job separately and assembled as they are laid. The oblique lips with their upturned outer edges afford excellent ledges 120 for the roadbed or ballast and prevent the rise of the tie or its creeping longitudinally of the railway, and the flanges at the extremities of the tie prevent its movement longitudinally or across the roadbed. If 125 130

the links are employed, they are preferably put in place before the metallic parts are laid, and their tangs upset as described—then the metal parts are placed on the road bed and the blocks inserted and bolted in position later.

Another feature of advantage of this tie is that, when any block requires removal or substitution, it can be accomplished without necessarily taking the tie out of the ballast. Simply withdraw the nut from the bolt, withdraw the bolt from place, and slip the block out of this end of the tie either longitudinally or vertically; and then replace it with another by a reversal of the operation. Preferably, of course, we would slip the block out longitudinally so as to withdraw it from beneath the rail, without necessarily even having to raise the rail. Finally the ballast which has been removed at the end of the block can be replaced and tamped in a manner well understood.

What is claimed as new is:—

1. The herein described composite tie made up of two metal members, each having an upright web and a horizontal web and a lip projecting obliquely from the angle between said webs, the outer edges of said lips being upturned, blocks of other material disposed between said metal members, and means for holding said blocks removably in place.

2. The herein described composite tie made up of two metal members, each having an upright web and a horizontal web and a lip projecting obliquely from the angle between said webs, the outer edges of said lips being upturned and both ends of the lip being downturned into flanges, other members interposed between the metal members, and means for holding all members together.

3. In a composite railway tie, the combination with two members of sheet metal,

each comprising an upright web beveled at its extremities and pierced near its ends 45 with holes, a horizontal web projecting toward the companion member from the lower edge of the upright web, and a two-ply lip standing oblique to and uniting both webs and consisting of an upper leaf projecting 50 from the lower edge of the upright web outward and downward, and a lower leaf continuing the outer edge of the upper leaf and extending inward and upward and united with the outer edge of the horizontal web; 55 of blocks interposed between said upright webs, and fastening means passing through the blocks and the holes in such webs.

4. In a composite tie, the combination with two spaced L-shaped members whereof 60 each has holes in its upright web and in its horizontal web, blocks interposed between said members, and fastening devices passing through the blocks and the holes in the upright webs; of links consisting of plates 65 standing on edge beneath the horizontal webs and each having upstanding tangs projecting through the holes in these webs and headed at their upper extremities.

5. In a composite tie, the combination 70 with two metal members of L-shaped cross section whose horizontal webs stand in the same plane but are spaced at their contiguous edges and are pierced with holes out of registry with each other, wood rail-supporting blocks disposed between said members, and connecting devices between the blocks and upright webs; of links underlying the horizontal webs and slightly oblique to a transverse line through the tie, each link 80 having upturned tangs at its extremity engaging two holes in the horizontal webs, for the purpose set forth.

In testimony whereof I affix my signature.

ALVIN E. HESS.
